United States Patent Office

Des. 177,818
Patented May 29, 1956

177,818

FINGER RING OR THE LIKE

Adolph Katz, Providence, R. I., assignor to Coro, Inc.,
New York, N. Y., a corporation of New York

Application May 5, 1955, Serial No. 35,839

Term of patent 7 years

(Cl. D45—10)

Fig. 1

Fig. 2

Fig. 3

Fig. 4

Fig. 1 is a front view of a finger ring or the like showing my new design.

Fig. 2 is an edge view thereof.

Fig. 3 is a rear view of Fig. 1.

Fig. 4 is a top plan view of a finger ring or the like.

I claim:

The ornamental design for a finger ring or the like, substantially as shown.
